(57) **CLAIM**

We claim the ornamental design for a physical training bench, as shown and described.

DESCRIPTION

FIG. 1 is a top, front perspective view of a physical training bench showing our new design;

FIG. 2 is a bottom, front perspective view thereof;

FIG. 3 is a front elevation view thereof;

FIG. 4 is a rear elevation view thereof;

FIG. 5 is a left-side elevation view thereof;

FIG. 6 is a right-side elevation view thereof;

FIG. 7 is a top plan view thereof; and,

FIG. 8 is a bottom plan view thereof.

The broken lines shown in FIGS. 1-8 depict portions of the physical training bench that form no part of the claimed design.

1 Claim, 8 Drawing Sheets
